UNITED STATES PATENT OFFICE.

WILLIAM A. WHITNEY, OF ROCKFORD, ILLINOIS.

PENCIL-SHARPENER.

1,330,105.

Specification of Letters Patent. Patented Feb. 10, 1920.

Application filed April 7, 1919. Serial No. 287,934.

To all whom it may concern:

Be it known that I, WILLIAM A. WHITNEY, a citizen of the United States, residing at Rockford, in the county of Winnebago and State of Illinois, have invented a new and useful Pencil-Sharpener, of which the following is a specification.

This invention has reference to improvements in pencil sharpeners and is designed 10 to provide a pencil sharpener whereby the pencil is automatically sharpened by blades which tend to maintain their edge indefinitely, and continuously present fresh edges to the portion of the pencil to be cut.

15 In accordance with the present invention, there is provided a rotatable series of circular dished blades movable over a plane surface through one portion of which the part of the pencil to be sharpened projects, 20 and the arrangement is such that after the blade has acted on the pencil the trailing portion of the blade is lifted away from the pencil so as not to drag over the same. The invention also contemplates readily adjustable means for determining the degree of pressure of the blades upon the surface over 25 which they travel.

The present application is for the same invention as was claimed in the allowed, for- 30 feited and abandoned application Serial Number 552,419, filed by this same applicant March 30, 1910.

The invention will be best understood 35 from a consideration of the following detail description taken in connection with the accompanying drawings forming a part of this specification, in which drawings,—

Figure 1 is a face view of the cutter plate and blades traversing the same, with the 40 chip receptacle in diametric sections.

Fig. 2 is a section on the line 2—2 of Fig. 1.

Fig. 3 is a top plan view of the face plate and parts carrying the same with the shaft 45 journal bearing partly in section, the cutters being omitted and the chip receptacle being removed.

Fig. 4 is a section on the line 4—4 of Fig. 1 on a somewhat larger scale.

50 Fig. 5 is a section on the line 5—5 of Fig. 1 on a larger scale, showing one of the cutters and its carrying arm.

Figs. 6 and 7 are detail perspective views

of the parts associated with the pencil carrier.

55

Fig. 8 is a perspective view of a guard used as a cover for the chip receptacle.

Referring to the drawings there is shown a chip receptacle 1 constituting the base or support for the pencil sharpener. In the 60 particular showing of the drawings this receptacle is indicated as cylindrical, but it will be understood that this shape is not mandatory.

The upper end of the receptacle is partly 65 covered by a block 2 which may be cast to the desired shape and may be of such size as to occupy somewhat less than one-half the area of the top of the receptacle. This block may be secured to the receptacle by 70 screws 3 or otherwise. One edge of this block is in chord relation to the receptacle 1 and there has formed on it a circular plate 4 preferably though not necessarily in one-piece with the block 2.

75 The block or plate 2 carries a journal bearing 5 at the rear of the plate 4 in substantially the axis of the plate 4, but at a slight angle thereto. The journal bearing 5 has a central passage 6 for a shaft 7 which 80 latter is reduced at each end as indicated at 8 and 9, respectively, and there screw-threaded, in the particular showing of the drawings. The face of the plate 4 is countersunk as indicated at 10 immediately surrounding the central opening 6 where it emerges at the face of the plate. The other end of the journal bearing is countersunk and screw-threaded and receives a bushing 11 with an accessible milled edge for ready 85 manipulation. The end 9 of the shaft 7 has applied thereto a crank handle 12 so that the user may readily impart rotative movement to the shaft 7 when desired.

90 The other end 8 of the shaft 7 receives 95 first a washer 13 and exterior thereto a nut 14 with a circumferential flange and between the washer 13 and nut 14 there is confined a spider 15 having in the particular showing of the drawings three radial arms 100 16 which as they progress toward the periphery of the plate 4 are bent forwardly into a curve constituting approximately half a circle and from the termination of this bent portion the arms progress radially 105 as indicated at 17, the tips of the extensions

17 terminating beyond the active face of the plate and over a peripheral rabbet 18 surrounding the active face of the plate.

At the junction of the curved portion of the arms and the extension 17, each arm carries an eccentric stud 19 projecting toward the face of the plate 4 and on each stud there is mounted a dished disk 20 having the edges 21 in a plane coincident with the plane of the active face of the plate 4. This produces upon the periphery of the disk a sharp cutting edge co-extensive with the circumference of the disk.

The arms 16 have a normal tendency toward the plate 4 and the plane portions of the disk are therefore held to the active face of the plate 4 with an elastic pressure commensurate with the tendency of the arms 16.

At one point in the rabbet 18 there is formed a cam projection 22 the purpose of which will presently appear. This projection 22 is in the path of the outer end of the arm extensions 17.

In tangential relation to the plate or disk 4 and formed on the back thereof is a socket member 23 projecting at one end beyond the edge of the disk or plate 4 and provided with a through longitudinal passage 24 of a size and shape adapted to receive a lead pencil. This socket member is in use normally in an upright position, assuming the reservoir or receptacle 1 to be resting on a plane horizontal surface, but the socket member 23 slants slightly to the plane of the active face of the disk or plate 4 and the lower end of the passage 24 opens into the face of the plate 4 as indicated at 25 while the back wall 26 of the passage 24 approaches the longitudinal axis of the passage 24 so that the shape of this end of the passage 24 is substantially conical or tapered. The upper end of the socket 23 is interiorly countersunk to receive the reduced end of a sleeve 26 having an exterior circular series of teeth 27 projecting slightly beyond the plane of the active face of the plate or disk 4, this plate being in cut slightly at the proper point as indicated at 28 to accommodate the teeth of the sleeve 26.

The outer end of the sleeve 26 is expanded circumferentially, as indicated at 29 and there countersunk and interiorly threaded to receive a bushing 30 terminating at the outer end in a milled manipulating radial flange. The purpose of the sleeve 30 is to confine to the outer end of the sleeve 26 an elastic ring or washer 31 so that the effective diameter of the passage 24 at this point may be controlled by the pressure of the sleeve or bushing 30 upon the ring 31. This provides a gripping means for a pencil introduced into the socket or pencil holder and accommodates the device to pencils of varying diameter within the usual limits of

pencils having an even diameter through- 65 out.

The sleeve 26 is held in its bearings formed by the reduced end entering the countersink at the upper end of the socket 23, by a finger 32 overriding the teeth 27 and held to the 70 socket by a screw 33 or otherwise. The same screw 33 may hold to the socket a spring finger 34 terminating in a guard 35 overriding the outer end of the bushing 30 and serving to guide a pencil into the passage 24 and there holding it in contact with the elastic washer 31. Either the washer 31 or the finger 34 may be omitted or both may be used together.

The receptacle 1 is usually provided with 80 a cover 36 extending to a point near the blade 16 and this cover may be provided with a chip directing guard 37 tending to cause chips cut from the pencil to fall into the receptacle 1.

The bushing 11 is usually provided with a left hand screw-thread so that its tendency when engaged by the adjacent portion of the crank handle 12 is to unscrew and thereby maintain the handle in position and 90 the blades 20 tightly against the base of the plate 4. This bushing 11 may be screwed into or out of its seat and so by bearing on the handle 12 determine the pressure with which the blades 20 move along the base of 95 the plate 4.

If, now it be assumed that a pencil has been introduced into the passage 24 its lower end will project slightly beyond the plane of the active face of the plate 4 so that when 100 the crank 12 is rotated the knives or cutters 20 will be brought in succession into engagement with the end of the pencil and pass along this end in the direction of the length of the pencil but the cutting edge will 105 traverse a shallow arc with relation to the length of the pencil so that the cut is to a slight extent a shear cut.

Each time an extension 17 passes the teeth 27, of the sleeve 26 they impart a 110 rotative movement of the sleeve a distance equal to the distance between two such teeth 27, and the parts are so related that this movement takes place after the preceding cutter has acted on the pencil.

The stud 19 constituting the axis of a blade 20 traverses a circular path concentric with the axis of rotation of the shaft 7. The frictional engagement of the entire cutting edges of the disks 20 with the face of the 120 plate or disk 4 together with the frictional engagement of these disks with the pins or studs 19 and the arms 16 cause a rotative movement of the disks about their axes to such an extent that the disks present new 125 cutting edges each time they traverse the pencil. This rotative movement of the disks with relation to their axes and the face

of the plate or disk 4 serves to maintain the cutting edges of the disks or cutters 20 so that they are always in good cutting condition. In other words the plate or disk 5 4 constitutes a scouring element, in contact with the surface of which the cutting edges of cutter disks are yielding held, to produce a self-sharpening effect.

After a disk has acted on the pencil the 10 opposite edge of the disk is dragged over the pencil and in order to prevent a dulling action on this portion of the disk or cutter 20 the cam projection 22 is so located as to raise or lift the corresponding arm 16 in a direction 15 away from the active face of the plate 4 and therefore at this time the pressure on the corresponding disk or cutter 20 is relieved and the inactive edge of the disk where traversing the pencil does not drag over the 20 same with any appreciable force. It will also be noted that the respective disks or cutters being moved away from or out of contact with the plate 4 at the lower end of the opening 25, will permit the chips, lead dust, 25 and other foreign matter which has dropped into the dished disk or cutters, to gravitate or drop downwardly from between the cutters and plate. This is of advantage for the reason that the presence of foreign matter 30 within the cutters or between the cutters and plate, would tend to decrease the efficiency of the self sharpening action.

By having the longitudinal axis of the shaft slightly out of coincidence with the 35 axis of generation of the plane face of the disk 4, the cutters 20 are brought with greater force against the plane face of the disk at the point where the passage 24 opens at the plane face of the disk and where the 40 pencil is acted upon than at other points on the face of the plate or disk 4 thus rendering the operation of the device easier than would be the case if the frictional engagement were the same throughout the active face of the 45 disk or plate 4.

The curvature of the arms 16 permits these arms being made longer than would be the case if they were truly radial and therefore these arms may be made amply strong and at 50 the same time quite elastic to give an elastic pressure of the cutters against the active face of the plate 4.

By having the automatic rotary movement of the cutters upon their supporting axes, 55 new cutting edges are continually presented and therefore that portion of the edge engaging the lead of the pencil does not become quickly dull while the rest of the blade is comparatively sharp, but the cutting edge remains substantially equally sharp throughout its circumference and any dulling of the edge which may take place on the cutter traversing the lead point of the pencil is remedied by the self-sharpening action of the cut-

ter in its rotary motion about its own axis 65 during the orbital motion about the axis of the shaft 7.

The finger 34 serves to hold the pencil so firmly against the elastic washer 31 as to cause a firm grip between the pencil and the 70 rotary sleeve 26, thus insuring the proper rotation of the pencil during the action of the sharpener. The elastic ring, washer or gasket 31 eliminates the use of holding springs which often become broken, while 75 the washer 31 is at all times readily renewable.

While three cutters have been shown and described it will be understood that a greater or a less number of cutters may be used as 80 may be found desirable, but usually three cutters are found to be most desirable in the commercial form of the machine.

I claim:

1. In a pencil sharpener, a member having 85 a grinding surface provided with a pencil-receiving opening, a dished cutter, and means for moving the cutter over the said opening and for pressing the same against the grinding surface during its movement. 90

2. In a pencil sharpener, a plate having a pencil-receiving opening, a rotary carrier, and a dished cutter disk rotatably carried by an eccentric portion of the carrier to move over the said opening and having its entire 95 edge portion frictionally held against the face of the said plate to be sharpened thereby.

3. In a pencil sharpener, a plate having a pencil-receiving opening, a rotary carrier, a rotary dished cutter disk carried by an eccentric portion of the carrier and having its edge portion frictionally bearing against the face of the plate to move over the said opening, and means for lifting the cutter away from off the plate when leaving the said 105 opening.

4. In a pencil sharpener, a plate having an opening, and a cam, a rotary carrier including a resilient arm, a rotary dished cutter carried by the arm to pass over the said opening, the arm holding the edge of the cutter yieldingly against the plate, and the cam being designed to force the arm away from the plate when the cutter leaves the opening. 110

5. In a pencil sharpener, a member having 115 a grinding surface provided with a pencil-receiving opening, a dished cutter, means for moving the cutter over the said opening and for pressing the cutter yieldingly against the grinding surface during the movement thereof, and means for lifting the cutter away from off the grinding surface when leaving the said opening. 120

6. A pencil sharpener having, in combination, means for holding a pencil, means for 125 cutting a pencil, and means arranged in co-operative relation to the pencil sharpening means, whereby during the operation of cut-

ting the pencil, the pencil cutting means will be sharpened.

7. In a pencil sharpening device, the combination of a support for pencils to be sharpened, a cutting member, means for driving said cutting member to sharpen the pencil, and sharpening means forming part of the device for sharpening said cutting member.

In testimony that I claim the foregoing as my own, I have hereto affixed my signature 10 in the presence of two witnesses.

WILLIAM A. WHITNEY.
